BUILDING SCREEN WALL

Gordon J. Clauss, 2705 Katherine St., Fort Myers, Fla.

Original design application Oct. 27, 1961, Ser. No. 67,290,
now design Patent No. 194,599, dated Feb. 19, 1963.
Divided and this application Feb. 11, 1963, Ser. No.
73,623

Term of patent 14 years

(Cl. D18—2)

FIG. 1

FIG. 2

FIG. 1 is a front elevational view of a building screen wall embodying my new design; and

FIG. 2 is a perspective view of one of the blocks shown in FIG. 1.

This application is a division of my copending application Serial No. D. 67,290, filed Oct. 27, 1961, now Patent No. D. 194,599.

I claim:

The ornamental design for a building screen wall, as shown.
